UNITED STATES PATENT OFFICE.

JAMES C. ARMSTRONG, OF BELOIT, WISCONSIN.

FAN.

1,424,391.

Specification of Letters Patent. Patented Aug. 1, 1922.

Application filed February 3, 1920. Serial No. 356,086.

To all whom it may concern:

Be it known that I, JAMES C. ARMSTRONG, a citizen of the United States of America, and a resident of Beloit, county of Rock, 5 and State of Wisconsin, have invented certain new and useful Improvements in Fans, of which the following is a specification.

This invention relates to fans, and especially to draft supplying means for use 10 in conjunction with the air-cooled radiators of internal combustion engines and the like.

The main objects of the invention are to provide an improved form of fan adapted 15 to occupy a minimum of space and having a greater efficiency than fans heretofore used; to provide such a fan of simple and durable construction capable of manufacture at a low cost with labor of ordinary 20 skill; and to provide a combined shield and draft flue in connection therewith adapted to avoid eddy current and friction losses and to accommodate the most efficient transmission of air to and from the fan.

25 An illustrative embodiment of this invention is shown in the accompanying drawings, in which—

Fig. 1 is mainly a vertical section through the fan and related parts along the axis 30 of the fan shaft.

Fig. 2 is mainly a front elevation of the fan and associated parts with part of the casing broken away.

In the construction shown in the drawings, the fan 1 is mounted on a frame 2 which may be part of an engine frame and is provided with a shaft 3 to which power may be applied by any of the means well-known in the art for driving the fan, as 40 for instance a pulley 3'.

In order to properly direct and control the flow of air, said fan is mounted in a draft passageway or flue 4 having an inlet aperture 5 in front of said fan and preferably concentric therewith, though somewhat smaller in diameter than the periphery of said fan.

On the upper part of said frame 2 is mounted a radiator 6 with which said flue 50 4 communicates for supplying air thereto.

The fan proper comprises a circular disk or back plate 7 and a peripheral series of oblong triangular blades or vanes 8 disposed radially on the front side thereof 55 with their wide ends disposed outward.

Each of said vanes is provided with a flange 9 on its radially disposed back edge so formed and positioned as to hold the main body of the vane substantially perpendicular to the plate 7. Said flanges are secured 60 by means 10 to the back plate, rivets being well adapted for this purpose.

In order to provide for convenient attachment of the back plate 7 to the shaft 3, a hub 11 is provided adapted to receive the 65 end of said shaft in snug fitting relation and provided with a flange 12 which is secured to said back plate by means 13, rivets also being well adapted for this use. A fastening 14, for example a pintle, is provided 70 to secure the hub in place on the shaft.

The flue wall 15 is so formed adjacent to the fan as to provide relatively small clearance space at the lower edge of the fan, as 75 at 16, and with gradually increasing clearance upward and at the sides of said fan, as at 17. The upper part 18 of the flue is amply wide to accommodate the necessary flow of air and at the top is turned back, as at 19, to discharge air into the radiator 80 6. The flue wall or casing is secured to the frame or base 2 by means of brackets 20, as shown in Fig. 2.

It is apparent that this fan is of such simple construction that, with the exception 85 of the hub, it may be made readily from sheet metal punchings of simple character and easy to form. Furthermore, in case of need for repairs resulting from accident or otherwise, the fan parts may be readily replaced and the fan kept in good condition 90 with but little trouble or expense.

Owing to the outwardly and divergently increasing width of the fan blades away from the center, the air is drawn in and 95 picked up thereby in a most modulated and efficient manner, especially adjacent to the center, and flung out radially, whereby a simple vortex is formed about the fan axis and the inefficient multiplicity of conflicting eddy currents produced by many of the prior fans is avoided. The practical advantage of these fans has been demonstrated by extensive use and their efficiency has been proven by carefully conducted tests carried 100 out under my observation and direction.

Although but one specific embodiment of this invention has been herein shown and described, it will be understood that numerous details of the construction shown may 115

be altered or omitted without departing from the spirit of this invention as defined by the following claims.

I claim:

5. 1. A large capacity, low pressure fan, comprising in combination a disk, a hub secured to the middle part of said disk, a driving shaft secured to said hub, and a plurality of elongated flat triangular vanes disposed perpendicularly to and radially on one of the faces of said disk with their narrow ends pointing inwardly.
10. 2. A low pressure, centrifugal fan adapted for large capacity and having right triangular vanes formed relatively wide at their outer ends and diminishing toward their inner ends in combination with a guide flue having substantially a full fan sized open front for the admission of a fluid medium directly to the diagonal edge side of the fan, said flue being formed and disposed to discharge said medium edgewise of said fan.
15. 3. A fan, comprising in combination an

axially imperforate disk, a hub secured coaxially to the middle part of said disk, a driving shaft secured to said hub, and a plurality of triangular vanes disposed radially on one of the faces of said disk, said hub having a bore to receive an end of said shaft and including a radial flange at one end to which said disk is fastened.

4. A large-capacity, high-speed, low-pressure ventilating fan of small size comprising a housing, in combination with a centrifugal paddle wheel of narrow shape having triangular blades disposed radially and pointing toward the fan axis, said housing including a rim part and a pair of plates spaced sufficiently to clear said wheel, one of said plates having an axial inlet aperture nearly equal to the size of said wheel and said rim part having a discharge aperture corresponding substantially therewith in effective size.

Signed at Chicago this 24 day of Jan.
1920.

JAMES C. ARMSTRONG.
